UNITED STATES PATENT OFFICE.

JAMES F. SCOTT, OF NEW YORK, N. Y.

POWER-CHAMBER.

1,180,947.

Specification of Letters Patent. Patented Apr. 25, 1916.

Application filed July 21, 1915. Serial No. 41,081.

To all whom it may concern:

Be it known that I, JAMES F. SCOTT, a citizen of the United States, and a resident of the city of New York, borough of Manhattan, in the county and State of New York, have invented a new and Improved Power-Chamber, of which the following is a full, clear, and exact description.

This invention relates to internal combustion engines and particularly to an improved power cylinder, and has for an object a provision of an improved construction which will eliminate the necessity for the use of lubricating oil in the cylinder.

Another object in view is to provide a cylinder which utilizes the expansion and contraction of the body thereof for operating a power member as, for instance, a connecting rod instead of utilizing the conventional piston.

A still further object in view is to provide an improved power cylinder which utilizes flexible plates and bracing means associated therewith for transmitting power produced in the cylinder by an explosion of combustible gases.

In the accompanying drawings, Figure 1 is a side view of a cylinder embodying the invention, a supporting frame being shown in connection therewith for more clearly illustrating how the cylinder operates; Fig. 2 is an enlarged fragmentary sectional view through part of the cylinder shown in Fig. 1, the position of the parts being shown greatly exaggerated; and Fig. 3 is a fragmentary sectional view through Fig. 2 approximately on line 3—3.

Referring to the accompanying drawings by numerals, 1 indicates the cylinder embodying the invention and 2 any suitable frame-work associated therewith. The upper part of the cylinder 1 is connected with what might be termed a head 2' which is adapted to receive in openings 3 and 4, inlet and outlet valves, while a suitable spark plug 5 is arranged at a convenient point for igniting the gases forced into the cylinder. The position of the parts forming cylinder 1 shown in Fig. 1 is a greatly exaggerated for the purpose of illustrating how the same expands and contracts for operating the connecting rod 6 which is connected with the crank shaft 7 in the usual manner.

In Figs. 2 and 3 will be seen details of the particular construction of the cylinder, the

various parts being shown greatly exaggerated especially in Fig. 2 for the purpose of illustration only. In practical construction, the expansion and contraction of a pair of disks approximately six inches in diameter, 60 will be probably about one-eighth of an inch instead of the large expansion shown in Fig. 2. As shown in this figure there are pairs of disks 8 and 9 which form the bellows construction of the cylinder 1 shown in Fig. 65 1. A ring 10 is provided with an internal slot in which the outer edges 11 and 12 of the disks or plates 9 and 10 are forced. As shown in Fig. 3, the ring 10 may be divided and secured together by a suitable bolt 13. 70 In forming the ring 10 a groove portion 14 is provided on one side and a groove portion 15 on the opposite side for seating the ends 16 of the bracing ribs 17. The inner ends 18 of ribs 17 contract at the center or 75 hub part of the cylinder except the ribs at the end of the cylinder, where they contact with a suitable nut 19, as shown in Fig. 1. A sleeve 20 threaded exteriorly is provided on which nuts 21 and 22 are mounted and 80 pinch the inner ends or flanges 23 together.

In order that the parts may fit properly together, tubular portions 24 are provided on each of the disks 8 and 9 so as to provide a proper bearing for seating the ends 18 of 85 the bracing ribs 17. It will be observed that the disks or plates 8 and 9 are comparatively thin flexible sheets formed of sheet metal of any desired kind. In forming the disks or diaphragms the same are formed 90 slightly dished and the action or vibratory movement of the disks or diaphragms is never more than the movement from the center line of the flat plane to the limit of the dished disk portion. The disk, 95 instead of being dished, may be corrugated in rings to aid in the movement thereof. The idea of forming the disks or diaphragms dished or corrugated is to arrange the fabric or construction of the disk 100 so as to subject the same to no strains that will tend to disintegrate the disk. Metal disks and also other materials may vibrate or bow to a certain extent without injuring or stretching the molecules of which the 105 particular material is made and when moving or vibrating to this extent there will be no injury to the material. If the vibration is such as to stretch the molecules the body or piece of material composed of those 110

2
molecules will soon fall apart or disintegrate. In forming the disks or diaphragms embodying part of the invention this law of materials is observed by dishing or corrugating the diaphragms and then allowing the diaphragms to move only a limited extent.

In operation, when the charge has been drawn into the cylinder 1 and compressed, 10 the spark plug 5 will ignite the combustible matter which, when the same explodes, will cause the various plates 8 and 9 to move apart centrally or expand as bellows. Each pair of plates, as heretofore described, will usually expand slightly, but where a large number of plates are used a comparatively large thrust is given to a power member, as for instance, connecting rod 6. The cylinder may be guided in its movement by any desired means, or have a cross head at the free end so that there will be no twisting of the various plates or disks 8 and 9 or of any of the other parts. It will be observed that this construction and arrangement is very desirable for explosive engines as a proper four-cycle movement is produced for drawing in fresh gases, forcing out the burnt products of combustion and compressing the gases after being drawn in previous to an explosion. After an explosion the return or collapsing of the plates or bellows construction will naturally force out all of the burnt products of combustion and the next movement will act as an intake in the usual manner of a four-cycle engine. By this construction and arrangement power is produced and transmitted to a point of utilization without the necessity or even a desirability of supplying the cylinder with lubricating oil, which oil is usually very troublesome in that it makes an undesirable deposit in the cylinder, as well as produces smoke when a comparative large amount has been placed in the cylinder.

45 Having thus described my invention I claim as new, and desire to secure by Letters Patent:

1. In a power cylinder of the character described, a plurality of collapsing units, 50 means for connecting said units together and reinforcing and bracing members for taking up the strain on said units.

2. In a power cylinder of the character described, an expansible unit adapted to be expanded by the explosion of combustible gases whereby power is produced without the production of friction in the cylinder *per se* and reinforcing and bracing members for taking up the strain on said expansible unit.

3. A power cylinder of the character described, a plurality of parts formed of pairs of diaphragms, said parts being adapted to be expanded by the explosion of combustible gases, reinforcing means engaging said

diaphragms for taking up the strain of said explosion and means for transmitting power from said cylinder.

4. In a power cylinder of the character described, an expansible structure formed of a plurality of flexible plates connected together at the periphery in pairs, each pair being connected together adjacent the center and reinforcing means engaging said plates, said means being formed of loosely positioned bars. 70 75

5. A power cylinder comprising a plurality of pairs of flexible plates connected together at the periphery, means for rigidly connecting same together adjacent their 80 hubs, there being an opening therethrough at the hubs for permitting communication from one pair of plates to the next adjacent pair and a set of bracing members arranged exteriorly of each plate for taking up the 85 strain on the plates.

6. A power cylinder of the character described, comprising a plurality of pairs of thin flexible disks connected together at the periphery, the disks having openings at their 90 centers, means for connecting said pairs together adjacent their centers, said means comprising a tubular member and locking members connected therewith for locking the disks rigidly together and a bracing 95 spider arranged against and on the outer face of each of the disks.

7. A power cylinder of the character described, comprising a plurality of disks having openings at their centers and connected 100 together in pairs at the periphery, the said pairs being connected together at their centers, and a plurality of bracing ribs arranged exteriorly of each of said disks, said bracing ribs being independent of the disks. 105

8. A power cylinder of the character described, comprising a plurality of flexible disks having an opening in the center, means for connecting said disks together in pairs, means for connecting each pair together at the center or hub, and a plurality of bracing ribs interlocking with the means for securing the brace together in pairs, said ribs contacting at their inner or hub ends, whereby said disks are reinforced. 110 115

9. A power cylinder comprising a plurality of pairs of disks secured together at the periphery, means for connecting said pairs of disks together at their centers, said means including a tubular member provided with a passage-way between each pair of disks, and stiffening reinforcing braces arranged exteriorly of the disks, said braces contacting at their hub ends. 120

10. A power cylinder comprising a bellows construction formed of a plurality of disks arranged in pairs, said pairs being secured together at the periphery, the respective pairs being also connected together at their centers, means presenting a communi- 125 130

cating passage-way between the various pairs, whereby an expansive fluid inserted into one of said pairs will be communicated to the remaining pairs whereby all of said 5 pairs will be expanded substantially simultaneously, loosely positioned bracing bars engaging the outer face of each of said disks, said bracing bars contacting at the hub end, and means engaging the outer end of said 10 bars for holding the same in contact with the disks.

11. A power cylinder of the character described, comprising a thin envelop and sup-

porting members for preventing the bursting of the envelop, said envelop being 15 formed from a plurality of pairs of plates and said reinforcing construction being formed from a plurality of bracing bars engaging the plates of said pairs.

In testimony whereof I have signed my 20 name to this specification in the presence of two subscribing witnesses.

JAMES F. SCOTT.
